UNITED STATES PATENT OFFICE.

MAJOR B. EGBERT, OF VANLUE, OHIO.

RAILROAD-RAIL.

SPECIFICATION forming part of Letters Patent No. 226,048, dated March 30, 1880.

Application filed January 17, 1880

To all whom it may concern:

Be it known that I, MAJOR BRITE EGBERT, of Vanlue, in the county of Hancock and State of Ohio, have invented certain new and useful Improvements in Rails for Railroads; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a perspective view, showing parts of two rails made and united according to the present invention. Fig. 2 is a perspective view, on reduced scale, showing entire rails united according to the present invention. Fig. 3 is a detail, showing the parts in vertical section.

The object of said invention is to produce a railroad-track that shall be essentially continuous bearing, and whereof the rail shall be lighter than is now usually made, and at same time, by the peculiar combination therewith of a fish-plate on each side, and of same length as the rail, provide a very strong and durable device; and the novelty consists more particularly in a L-rail made considerably lighter than is usual now, and having a plate on each side firmly fixed upon the rail and so applied as that they shall fit snugly between the lower flange and the tread and extend from middle to middle of each rail, and thus form substantially a continuous rail, all as will now be more fully set out and explained.

In the accompanying drawings, A denotes railroad-track rails, in most respects like what is known as L-rails; but the peculiarity of the present rails is that they are very considerably lighter than the rails now in ordinary use.

In Fig. 1 are shown at A A the half-parts of two rails, and these are united to each other

by the side plates, B, which will extend from the center to the center of the length of each rail. These plates are fastened to the rail in any usual or ordinary way.

I have now illustrated how this can be done in one way, viz., by bolts *b* passing through both plates B, and also the rail, which is between and headed.

The plates B are made of metal, and, being set on their edges snugly between the lower flange and the tread and firmly secured to the rail, will materially aid to support and strengthen it; and, since the ends of the adjoining plates meet at the middle of each rail, there is afforded practically a continuous rail, which will give a very smooth and continuous bearing.

It will be observed that the side plates sustain the tread at the point of hardest wear, and assist in the most effective manner in strengthening this portion of the rail.

By this invention is afforded a strong, cheap, and easily-constructed railroad-track.

Having thus described my invention, what I consider new, and desire to secure by Letters Patent, is—

In a railroad-track, the combination, with rails made somewhat lighter than is now usual, of pieces set edgewise on each side and snugly between the tread and bottom flange of the rails, sustaining the outer edge of the tread, and extending lengthwise from about center to center of each rail, and firmly united to each other and the rails between, substantially as and for the purposes set forth.

In testimony that I claim the foregoing I have hereinunto set my hand this 14th day of November, 1879.

MAJOR BRITE EGBERT.
